LUBRICATING APPARATUS

Filed March 17, 1920

Inventor
Ernest W. Davis

William Brasbury
Attorneys.

UNITED STATES PATENT OFFICE.

ERNEST W. DAVIS, OF OAK PARK, ILLINOIS, ASSIGNOR, BY MESNE ASSIGNMENTS,
TO THE BASSICK MANUFACTURING COMPANY, A CORPORATION OF DELAWARE.

LUBRICATING APPARATUS.

Application filed March 17, 1920. Serial No. 366,626.

To all whom it may concern:

Be it known that I, ERNEST W. DAVIS, a citizen of the United States, and resident of Oak Park, in the county of Cook and State of Illinois, have invented a certain new and useful Improvement in Lubricating Apparatus, of which the following is a full, clear, concise, and exact description, reference being had to the accompanying drawings, forming a part of this specification.

My invention relates to improvements in lubricating apparatus, and is especially concerned with improvements in lubricating apparatus of the type disclosed in the patent to Arthur V. Gullborg, No. 1,307,733, of June 24, 1919.

The objects of my invention are:

First: To provide a lubricant compressor comprising a barrel or cylinder having a piston slidable therein and operated by a screwthreaded piston rod, the barrel being provided with a flexible discharge conduit, and means whereby either end of the flexible discharge conduit may be quickly and easily attached to and detached from the compressor barrel;

Second: To provide a compressor of the type described, wherein the discharge conduit is provided with a coupling member at each end thereof, so constructed that it may be attached either to the barrel of the compressor or to the nipples, to which lubricant is supplied by the compressor;

Third: To provide the discharge conduit with coupling members of a novel type, so constructed that when the coupling members are detached either from the compressor or from the nipple they will prevent the escape of lubricant from the discharge conduit; and

Fourth: To provide a coupling member of such construction that it is unnecessary to relieve the pressure on the lubricant in the compressor, before detaching the coupling member from the nipple.

Other objects will appear as this description progresses, reference being had to the accompanying drawings, in which—

Figure 1 is a side elevation of my improved compressor, showing the free end of

the discharge conduit connected with a nipple adapted to be secured to a bearing to be lubricated, portions of the discharge conduit being broken away;

Figure 2 is a central longitudinal section on an enlarged scale, through the coupling member attached to the lubricant receiving nipple; and

Figure 3 is a view similar to Figure 2, but showing the coupling member at the opposite end of the discharge conduit connected with the nipple secured to the discharge end of the compressor; and

Figure 4 is a side elevation of a coupling member so constructed that it is not necessary to relieve the pressure on the lubricant in the compressor to make it possible to detach the coupling member from the nipple.

Throughout the several views similar reference characters will be used for referring to similar parts.

Where lubricant compressors of the type disclosed in the patent to Arthur V. Gullborg, referred to above, and of the type disclosed in this application, are employed, the said lubricator, comprising a barrel, one end of which is provided with a cap, when it is desired to fill the compressors with lubricant the cap is detached and in order to permit the escape of air from the compressor barrel during the filling operation, the discharge conduit is likewise detached from the opposite end of the barrel. It is also desirable to detach the discharge conduit from the compressor whenever the compressor is placed in a tool box, as this permits the compressor to be stored in a smaller space without bending the discharge conduit. It has heretofore been the experience that when the discharge conduit is detached from the barrel, there may be a small air bubble compressed in the lubricant intermediate the ends of the discharge conduit, which expands, and especially so in hot weather, forcing lubricant from both ends of the discharge conduit.

One of the objects of my invention, as stated above, is to provide means for closing both ends of the discharge conduit when it is detached from the compressor barrel,

and from the nipple, so as to prevent discharge of lubricant from the discharge conduit.

When a coupling member, such as that disclosed in the patent to Gullborg, is attached to a nipple and the compressor is actuated to force lubricant therethrough, the coupling member becomes locked to the nipple by the reaction of the lubricant pressure upon the end of the nipple, and it is necessary to relieve the pressure on the lubricant by retracting the piston in the compressor, before the coupling member can be easily detached from the nipple. Consequently, another object of my invention is to provide a coupling member so designed that it can be released from the nipple without first relieving the pressure on the lubricant. With such a coupling member it is necessary to provide means to prevent the escape of lubricant from the free end of the discharge conduit when the coupling member at this end of the discharge conduit is disconnected from a nipple.

Referring to the drawings, the reference character 5 indicates the barrel or cylinder of my improved compressor, which is provided at one end with a cap 6, detachably secured thereto in any desired manner.

A piston (not shown) is slidably mounted in the compressor barrel, and is actuated by means of the screw-threaded rod 7, having the handle 8. The opposite end of the compressor is provided with a hollow boss 9, into which is screwed the nipple 10, shown in side elevation in Figure 3. This nipple is similar to those disclosed in the patent to Arthur V. Gullborg, referred to above, except that it is not provided with a closure. The pin 11 provides means for co-acting with the bayonet slots in the coupling members about to be described, for securing one end of the discharge conduit to the compressor.

The reference character 12 indicates a lubricant receiving nipple, one end of which is provided with screwthreads 13, whereby it may be attached to a bearing to be lubricated, and the other end of which is provided with a pin 14, adapted to co-act with the bayonet slots in the coupling members, for making a detachable connection with the coupling members. The nipple 12 is provided with a spring pressed closure 15 similar to that shown in the Gullborg patent.

I shall now describe my improved coupling member, one of which is attached to each end of the flexible discharge conduit 16 of the compressor. This coupling member 60 comprises a sleeve 17, the end 18 of which is provided with an enlarged bore adapted to receive one end of the flexible discharge conduit 16, this end of the sleeve being soldered or otherwise secured to the end of the flexible conduit. Before the end of the flexi-

ble conduit is inserted in this end of the sleeve 17 a finishing ferrule 19 is soldered thereto. An annular flange 20 projects from the inner wall of the sleeve 17 at a point intermediate its ends, forming a discharge port 21, and a valve seat 22, which is adapted to co-act with the valve 23. The valve 23 is provided with a stem 24, which is hollow throughout a portion of its length, to provide a passageway for the lubricant, which communicates with the space between the hollow valve stem and the walls of the end 25 of the sleeve 17 through the ports 18 formed in the side walls of the hollow stem. The open end of the hollow stem registers with the discharge port 26 in the cup leather or gasket 27, which is slidably mounted in the end 25 of the sleeve 17, and with the opening in the end of the nipple 12, which receives the lubricant. The open end of the valve stem is flanged over on the washer 28, which acts as a follower for the cup leather or gasket 27, and as an abutment for one end of the spiral spring 29, the other end of which rests against the flange 20.

An outer sleeve, formed of the two parts 30 and 31, joined by the screwthreaded connection 32, is rotatably mounted upon the sleeve 17 and held thereon by means of the annular rib 32', projecting from the outer wall of the sleeve 17. The bore of the outer end of the rotatable sleeve is slightly smaller than the bore of the outer end 25 of the sleeve 17, and thus forms a shoulder 33 tending to limit the outward movement of the gasket 27 under the influence of the spring 29. It will, of course, be apparent that the valve 23 performs the same function when it is closed.

The coupling member at the opposite end of the flexible conduit, which is shown in Figure 3, as being connected with the nipple 10, is similar in all respects to the coupling member shown in Figure 2, which I have just described. I shall now describe the mode of operation of my improved apparatus. When the coupling members at the opposite ends of the discharge conduit are connected with the compressor barrel and the lubricant receiving nipple, as shown in Figure 1, the ends of the nipples contact with the gaskets, forcing them inwardly against the pressure of the springs 29, and displacing the valves 23 from their seats 22. In this manner a continuous passageway is afforded from the compressor to the nipple, and upon actuation of the piston in the compressor lubricant will be forced into the nipple. When a sufficient quantity of lubricant has thus been forced into the nipple, with the type of coupling shown in Figure 1, wherein the transverse portions 35 of the bayonet slots are recessed, as shown at 36, to provide means for locking the coupling member to the nipple, it is necessary first

to relieve the pressure on the lubricant in the compressor before the coupling member can be detached from the nipple. After pressure has been relieved the coupling member is detached from the nipple in the usual manner, but in so doing the gasket 27 under the pressure of the lubricant and the spring 29 will remain in sealing contact with the end of the nipple, until the valve 23 seats 10 upon the valve seat 22, so that when the coupling member is completely detached from the nipple, there will be no escape of lubricant from the free end of the flexible discharge conduit.

15 With a coupling member similar in all respects to those disclosed in Figure 1, 2 and 3, except that the transversely extending portion 35' of the bayonet slot extends at right angles to the longitudinally extending portion of the slot and is provided with straight edges, it is unnecessary to relieve the pressure in the compressor before detaching the coupling member from the nipple, as the only resistance which must be overcome is that of the friction of one edge 25 of the slot on the pin. With such a construction it is of course highly necessary to provide means to prevent the escape of lubricant from the free end of the discharge 30 conduit when the coupling member is detached from the nipple. My improved coupling accomplishes this result in a very efficient manner.

It will be clear from the above description 35 that I have provided means whereby a discharge conduit can be quickly and easily attached to and detached from a compressor barrel, and which embodies means for preventing the escape of lubricant from both 40 ends of the discharge conduit.

While I have described the details of the preferred embodiment of my invention, it is to be clearly understood that my invention is not limited to these details, but is 45 capable of other adaptations and modifications within the scope of the appended claims.

Having thus described my invention, what I claim is:

- 50 1. The combination with a nipple for receiving lubricant, of a lubricant compressor having means for discharging lubricant, comprising a nipple, a discharge conduit for said compressor, provided at each end with a coupling member comprising a sleeve fixedly secured to said conduit and provided intermediate its ends with a port having a valve seat, a valve having a solid head for coacting with said seat, and a hollow stem 55 projecting through said port, there being a clearance space between said stem and the walls of said port, the said valve opening inwardly and the stem of said valve being provided with a lateral port, a gasket secured to the outer end of said stem, and adapted to bear against said nipple and the inner walls of said sleeve, said gasket being provided with a port in registry with the open end of said stem, a spring for closing said valve on its seat, and means for securing said sleeve to said nipple.
- 60 2. The combination with a nipple for receiving lubricant, of a lubricant compressor, comprising a nipple, a discharge conduit for said compressor, provided at each end with a coupling member comprising a sleeve fixedly secured to said conduit and provided intermediate its ends with a port having a valve seat, a valve having a solid head for coacting with said seat, and a hollow stem 65 projecting through said port, there being a clearance space between said stem and the walls of said port, the said valve opening inwardly and the stem of said valve being provided with a lateral port, a gasket secured to the outer end of said stem, and adapted to bear against said nipple and the inner walls of said sleeve, said gasket being provided with a port in registry with the open end of said stem, a spring for closing said valve on its seat, and means for securing said sleeve to said nipple.
- 65 3. The combination with a nipple for receiving lubricant, of a discharge conduit provided at its free end with a coupling member comprising a sleeve fixedly secured to said conduit and provided intermediate its ends with a port having a valve seat, a valve having a solid head for coacting with said seat, and a hollow stem projecting through said port, there being a clearance space between said stem and the walls of said port, the said valve opening inwardly and the stem of said valve being provided with a lateral port, a gasket secured to the outer end of said stem, and adapted to bear against said nipple and the inner walls of said sleeve, said gasket being provided with a port in registry with the open end of said stem, a spring for closing said valve on its seat, and means for securing said sleeve to said nipple.
4. The combination with a discharge conduit for a lubricant compressor, of a coupling member comprising an inner sleeve, one end of which is rigidly secured to one end of said discharge conduit, a valve seat in said inner sleeve intermediate the ends thereof, a centrally apertured gasket slidably mounted in the other end of said inner sleeve, an outwardly closing valve for co-acting with said seat, a hollow valve stem extending from said gasket to said valve, a

bear against said nipple, and the inner walls of said sleeve, said gasket being provided with a port in registry with the open end of said stem, a spring confined between a portion of said sleeve and said gasket for closing said valve on its seat, and means for securing said sleeve to said nipple, comprising a second sleeve rotatably mounted on said first mentioned sleeve, said second sleeve and said nipple being provided with co-acting means for effecting a detachable connection.

2. The combination with a nipple for receiving lubricant, of a lubricant compressor having means for discharging lubricant, comprising a nipple, a discharge conduit for said compressor, provided at each end with a coupling member comprising a sleeve fixedly secured to said conduit and provided intermediate its ends with a port having a valve seat, a valve having a solid head for co-acting with said seat, and a hollow stem projecting through said port, there being a clearance space between said stem and the walls of said port, the said valve opening inwardly and the stem of said valve being provided with a lateral port, a gasket secured to the outer end of said stem, and adapted to bear against said nipple and the inner walls of said sleeve, said gasket being provided with a port in registry with the open end of said stem, a spring for closing said valve on its seat, and means for securing said sleeve to said nipple.

3. The combination with a nipple for receiving lubricant, of a discharge conduit provided at its free end with a coupling member comprising a sleeve fixedly secured to said conduit and provided intermediate its ends with a port having a valve seat, a valve having a solid head for co-acting with said seat, and a hollow stem projecting through said port, there being a clearance space between said stem and the walls of said port, the said valve opening inwardly and the stem of said valve being provided with a lateral port, a gasket secured to the outer end of said stem, and adapted to bear against said nipple and the inner walls of said sleeve, said gasket being provided with a port in registry with the open end of said stem, a spring for closing said valve on its seat, and means for securing said sleeve to said nipple.

4. The combination with a discharge conduit for a lubricant compressor, of a coupling member comprising an inner sleeve, one end of which is rigidly secured to one end of said discharge conduit, a valve seat in said inner sleeve intermediate the ends thereof, a centrally apertured gasket slidably mounted in the other end of said inner sleeve, an outwardly closing valve for co-acting with said seat, a hollow valve stem extending from said gasket to said valve, a

spring in said inner sleeve for urging said valve to its closed position, an annular rib extending outwardly from said inner sleeve, and an outer sleeve rotatably mounted on
5 said inner sleeve, said outer sleeve comprising two parts detachably connected, one of said parts resting against said annular rib.

In witness whereof, I hereunto subscribe my name this 9th day of March, 1920.

ERNEST W. DAVIS.
